(57) **CLAIM**

The ornamental design for a door handle, as shown and described.

DESCRIPTION

FIG. 1 is a front, left side, top perspective view of a door handle showing our new design;

FIG. 2 is a rear, left, top perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

A second embodiment of the claimed design for the door handle is a mirror image of the door handle as shown in FIGS. 1 to 8.

The broken lines and the de-emphasized areas located within the broken lines in FIGS. 1-8 represent portions of the door handle that form no part of the claim.
